[57] **CLAIM**

The ornamental design for a base for a desk pen set and calendar or similar articles, as shown and described.

DESCRIPTION

FIG. 1 is a perspective view of a base for a desk pen set and calendar or similar articles showing my new design;
FIG. 2 is a top plan view;
FIG. 3 is a left side elevational view, the right side elevational view being a mirror image thereof;
FIG. 4 is a front elevational view;
FIG. 5 is a rear elevational view; and
FIG. 6 is a bottom plan view.
